(57) **CLAIM**

The ornamental design for a concrete trough attachment with a plurality of legs, as shown and described.

DESCRIPTION

FIG. 1 is an isometric view of a concrete trough attachment with a plurality of legs, showing my new design.

FIG. 2 is a typical side view of the design of FIG. 1, where the opposed side view is a mirror image thereof.

FIG. 3 is a typical end view thereof, where the opposed end view is a mirror image thereof.

FIG. 4 is a top plan view thereof; and,

FIG. 5 is a bottom plan view thereof.

1 Claim, 3 Drawing Sheets

FIG. 1

FIG. 2

FIG. 3

FIG. 4

FIG. 5
